DESIGN FOR A BOTTLE

Rudolph Samuels, Los Angeles, Calif., assignor to Carr-Lowrey Glass Company, Baltimore, Md.

Application July 20, 1939, Serial No. 86,133

Term of patent 14 years

To all whom it may concern:

Be it known that I, Rudolph Samuels, a citizen of the United States, residing at Los Angeles, in the county of Los Angeles and State of California, have invented a new, original, and ornamental Design for a Bottle, of which the following is a specification, reference being had to the accompanying drawing, forming part thereof.

my new design.

I claim:

The ornamental design for a bottle, as shown.

RUDOLPH SAMUELS.
